Primary Examiner — Brett Miller*Assistant Examiner* — Nader Abadir(74) *Attorney, Agent, or Firm* — ScienBiziP, P.C.**CLAIM**

The ornamental design for a juicer, as shown and described.

DESCRIPTION

FIG. 1 is a front, right, and top perspective view of a juicer, showing my design.

FIG. 2 is a rear, left, and bottom perspective view of the juicer in FIG. 1.

FIG. 3 is a front view of the juicer in FIG. 1.

FIG. 4 is a rear view of the juicer in FIG. 1.

FIG. 5 is a left side view of the juicer in FIG. 1.

FIG. 6 is a right side view of the juicer in FIG. 1.

FIG. 7 is a top view of the juicer in FIG. 1.

FIG. 8 is a bottom view of the juicer in FIG. 1; and,

FIG. 9 is another front, right, and top perspective view of the juicer in FIG. 1 in an open state.

The broken lines shown in the drawings are included for the purpose of illustrating portions of the juicer that form no part of the claimed design.

1 Claim, 9 Drawing Sheets(56)
